UNITED STATES PATENT OFFICE

120,682

DESIGN FOR A SCARF OR SIMILAR ARTICLE

Virginia Winston, Jackson Heights, N. Y.

Application April 4, 1940, Serial No. 91,468

Term of patent 3½ years

To all whom it may concern:

Be it known that I, Virginia Winston, a citizen of the United States of America, residing in Jackson Heights, in the county of Queens and State of New York, have invented a new, original, and ornamental Design for a Scarf or Similar Article, of which the following is a specification, reference being had to the accompanying drawing, forming part thereof, wherein the figure shows approximately one half of the scarf, the design on the remaining portion being identical with that shown.

I claim:

The ornamental design for a scarf or similar article, substantially as shown and described.

VIRGINIA WINSTON.
